Ronald Nicol, Trenton, N.J., assignor to Heinemanns
Electric Company, Trenton, N.J.

Filed Feb. 4, 1975, Ser. No. 547,052

Term of patent 14 years

Int. Cl. D13—03

U.S. CL. D26—13 R

FIG. 1

FIG. 2

FIG. 3

FIG. 4

FIG. 5

FIG. 6

FIG. 7

FIG. 1 is a front perspective view of an enclosure for circuit breakers showing my design;

FIG. 2 is a back perspective view thereof and showing the other side;

FIG. 3 is a front elevational view thereof;

FIG. 4 is a back elevational view thereof;

FIG. 5 is a side elevational view thereof showing the side illustrated in FIG. 1;

FIG. 6 is a top plan view thereof; and

FIG. 7 is a bottom plan view thereof.

The broken lines are for illustrative purposes only.

I claim:

The ornamental design for an enclosure for circuit breakers, as shown and described.
